 corporation of South Carolina

Application May 3, 1938, Serial No. 205,825

3 Claims. (Cl. 229—5.5)

This invention relates to containers of the type designed and intended for use in the packaging and dispensing of liquids, such for instance as lubricating oils.

5 Primarily the invention is concerned with containers fabricated entirely of paper and which, after having been emptied, can readily be disposed of by burning, having no metallic parts. A principal objective of the invention is the provision of an all-paper container of low cost, which is self-supporting, sufficiently rugged to withstand all shocks incident to transportation and handling, and which is so treated with a moisture repelling coating that its oil or other 10 liquid contents cannot penetrate its fibrous walls to weaken the same and possibly result in leakage. I have discovered that a liquid will rapidly penetrate into and saturate a paper sheet when it is brought into contact with an edge 15 of the sheet, the liquid travelling by capillary action rapidly in the plane in which the fibers are deposited during the formation of the sheet. Penetration of liquid transversely into and through a paper sheet when applied to a side 20 surface of the sheet proceeds at a much slower rate. Hence the present invention contemplates the fabrication of containers formed of paper in sheet form, in which the several component elements of the container are so shaped and so 25 assembled together that the liquid with which the container is filled does not have at any time access to the edge of a sheet.

It is also highly desirable that a container when fabricated of paper be rendered resistant 30 to the penetration of moisture from without since the strength of its wall decreases as the moisture content thereof increases and the penetration of a substantial amount of moisture into the wall of a paper container from the outside thereof will 35 result in its early failure. The invention contemplates, therefore, a paper container both the exterior and interior surfaces of which have been rendered impervious to moisture. All interior surfaces of the container are coated with 40 a suitable moisture-proof coating composition. The exterior surfaces thereof may be so treated or may be protected against moisture by the application of a moisture-resistant envelope. This envelope may be in the form of a label secured to 45 the outer surface of the container by means of an adhesive or in the form of a tubular envelope telescoped over the container body and secured in position, for instance by crimping the ends of the tube inwardly over the container end- 50 closures.

Various forms of the invention are indicated in the accompanying drawings, in which:

Figure 1 is a side elevation of a preferred form of container, partially broken away to show the details of construction; 5

Figure 2 is an axial section through portion of a container of the type shown in Figure 1, the end closure construction of the container of Figure 2, however, differing in minor respects from the end closure of the container shown in Figure 10 1; 10

Figure 3 is a plan view on a reduced scale of the paper blank from which the body of the container shown in Figure 2 is fabricated; 15

Figure 4 is a view similar to Figure 2, the section being taken, however, through a third form of container;

Figure 5 shows partially in elevation and partially in section a container of the type shown in Figure 1, one end of the container having been 20 removed, and a pouring funnel being positioned thereon;

Figures 6 and 7 are views similar to Figure 1 but showing modified forms of containers.

The principal member of each of the containers shown comprises a tubular body, preferably a hollow cylindrical body formed by winding a blank upon a cylindrical mandrel, the wall being built up of several plies or convolutions of paper secured together by an adhesive. The tubular body of the container shown in Figure 1 is indicated at 10 and is three plies in thickness. The closures for the end of the body 10 are identical and one such closure will be described. It comprises two discs, an inner disc 11 and an outer disc 12, the inner disc 11 having a peripheral cylindrical flange 13 and the outer disc 12 having a peripheral cylindrical flange 14. The inner disc lies wholly within the container body and the cylindrical outer surface of its flange 13 is 40 secured to the inner surface of the body 10 by a suitable adhesive. It will be observed that short, cylindrical portions of the body 10, at the ends thereof, are inwardly displaced. This is accomplished by rolling or pressing operations. The 45 peripheral flange 14 of the outer closure disc 12 fits snugly in the recess thus provided by the inward displacement of the ends of the tubular body, the outer cylindrical surface of flange 14 in effect comprising an extension of the outer 50 cylindrical surface of the body 10 so that a paper sheet 15 in the nature of a label or outer envelope which is secured to the outer surface of the member 10 and which overlaps the flanges 14 will be truly cylindrical from end to end. 55

Prior to assembling the several parts of the container the inner surface of the container body 10 is thoroughly coated with a film of a substance having the capacity to resist the penetration of the liquid commodity which the container is intended to receive. Where the container is primarily designed to receive and dispense oils this coating may advantageously be glue, since glue is resistant to the action of oils and oily substances. Thereafter the inner disc 11 of the end closure is applied after the face of this disc, and the exterior surface of its peripheral flange 13, has been coated with a suitable moisture penetration-resisting film. The film of coating material on the inner surface of the body 10 is indicated at 16 and that on the disc 11 at 17, these two films merging in the cylindrical joint between flange 13 and the cylinder wall. Prior to assembly of the closure disc 12 a coating 18 is applied to one face and to the cylindrical inner surface of flange 14. Advantageously this coating material may also be glue and the disc is applied while the glue is moist. To prevent the escape of air trapped between the discs 11 and 12 the outer disc 12 is perforated at 19 and to effect closure of this perforation after assembly has been completed, a sufficient quantity of coating substance is placed on the inner surface of disc 12—this coating substance running into the aperture 19 and securing the same after assembly of disc 12 has been completed. Naturally the container is charged before the application of the second end closure. The label 15 applied exteriorly is preferably of moisture-resisting material such as thin paper, treated with a substance to render it moisture-proof. The container thus formed costs but little and is sufficiently strong to stand dropping or rough usage without leaking.

When its contents are to be removed one entire end may be taken off, as for instance by cutting the body 10 and label 15 along the line a—a, Figure 1. Thereafter a paper funnel 20, in the form of a hollow frustum of a cone is slipped over the open end of a container so that its contents may be readily discharged into a restricted opening upon inversion of the container and funnel. Both container and funnel may be destroyed by burning after the contents of the container have been removed.

In Figure 2 a slightly modified form of container is shown in which the recess for the reception of the flange 22 of the outer closure disc member 23 is formed by a cutting or grinding operation. Or, alternatively, the body 24 of the container may be fabricated of a blank or paper sheet such as indicated at 25 in Figure 3, that portion of the sheet which will comprise the last or outer convolution of the body after the sheet has been wound onto the mandrel being cut away as indicated at 26 so that, after the cylindrical body has been completely formed it will have exterior annular recesses or grooves at its ends which terminate in well defined shoulders, one of which is shown in Figure 2. A label or envelope of moisture-proof material, such as coated or impregnated paper, is indicated at 27 in Figure 2 and is applied in the same manner, and for the same purpose, as is the generally similar envelope 15 shown in Figure 1. Layers of coating material upon the body and end discs are indicated respectively at 28, 29 and 30.

The form of the invention disclosed in Figure 4 is generally similar but in this form the ends of the tubular body 35 are not recessed to receive

the cylindrical peripheral flange 36 of the outer closure disc 37. No label or envelope is applied but an inner closure disc 38 is provided, the surfaces of body 35 and the flanged discs 37 and 38 being coated prior to assembly, as before.

In the form of the invention disclosed in Figure 6 the flanged end discs 40 and 41 are nested as shown and the moisture-proof envelope 42 covers the entire outer surface of the cylindrical paper body 43 and has its end margins turned 10 and extending between the flanges 44 and 45 of the end closure discs 40 and 41, respectively, being secured to these flanges by a suitable adhesive. In the case of this form of the invention the container body 43 is interiorly coated as 15 before, likewise the inner surfaces of both discs 40 and 41, and the flanges of such discs. If desired, the discs 40 and 41 may be dipped in a coating substance such as glue so that all surfaces thereof are coated with the moisture-resist- 20 ing substance.

In the form of the invention shown in Figure 7 the body 50 has its ends inwardly pressed or displaced and each end closure comprises an inner disc 51 and an outer disc 52, the flange 53 of the inner disc being attached to the cylindrical inner surface of the inwardly displaced end portion of the body 50 and the flange 54 of the outer disc 52 lying within the recess formed by the inward displacement of the end of the body. 30 Instead of an envelope which is secured to the outer surface of body 10 by means of an adhesive, as in the case of the forms of the invention shown in Figures 1, 2 and 6, an envelope 55 which comprises a paper tube is telescoped over 35 the body 50, its inner surface closely fitting against the outer surface of body 50. After it is thus assembled the ends of the envelope 55 are laterally and inwardly crimped as shown in Figure 7 so as to overlie and engage the outer end 40 disc 52, the envelope by this means being retained in position and likewise serving to positively hold the closure discs 51 and 52 in position. The container thus formed is particularly well suited to withstand mechanical shock. In its formation 45 all surfaces which may be exposed to contact with the liquid commodity within the container are adequately coated with moisture-resisting substance and this coating material is applied to the mutually facing surfaces of discs 51 and 52 so that these surfaces are rigidly attached to each other. If desired, the closure discs 51 and 52 may be dipped in the coating material prior to 50 assembly with the body 50.

In each instance the closure discs are fabricated of paper and are formed by pressing or drawing a flat paper sheet into the form of a flanged disc. The cost of each element of the container is relatively slight and all such elements may be quickly and easily assembled to form the completed container. The container will hold a body of liquid for a long period of time without weakening in the slightest, is readily opened, and may thereafter be easily disposed of by burning.

Having thus described the invention, what is claimed as new and desired to be secured by Letters Patent is:

1. In a paper container, a cylindrical body comprising a convolutely wound strip of paper, the outer convolution being narrower than the inner convolutions, thus providing an external annular recess at one end of said body, an end closure disc seated against the end of said body and having a peripheral flange lying in said re- 70 75

cess, a second closure disc within the said body and provided with a peripheral flange engaging the inner wall surface of the body and extending toward the first disc.

5 2. In a paper container, a cylindrical body comprising a convolutely wound strip of paper, the outer convolution being narrower than the inner convolutions, thus providing an external annular shoulder adjacent and facing one end 10 thereof, a closure disc overlying the end of the body and having a peripheral cylindrical flange encircling the container end and seating against said shoulder, and a closure disc within the end of said body also provided with a cylindrical flange, the side of said flange engaging the inner 15 wall surface of said body and its edge abutting said exterior closure disc.

3. In a paper container, a cylindrical body comprising a convolutely wound strip of paper, the outer convolution being narrower than the inner convolutions, thus providing an external annular recess at one end of said body, an end 5 closure disc seated against the end of said body and having a peripheral flange lying in said recess, a second closure disc within the said body and provided with a peripheral flange engaging the inner wall surface of the body and extending 10 toward the first disc, a moisture-proof envelope encircling said cylindrical body, the cylindrical margin of said envelope overlapping and being secured to the outer surface of the flange of the 15 end closure disc.
